UNITED STATES PATENT OFFICE.

CHARLES NELSON, OF ST. LOUIS, MISSOURI, ASSIGNOR TO C. NELSON MANUFACTURING COMPANY, OF ST. LOUIS, MISSOURI, A CORPORATION OF MISSOURI.

BRICK-ICE-CREAM CONTAINER.

Application filed October 3, 1921. Serial No. 505,143.

To all whom it may concern:

Be it known that I, CHARLES NELSON, a citizen of the United States, and resident of the city of St. Louis and State of Missouri, have invented certain new and useful Improvements in Brick-Ice-Cream Containers, of which the following is a specification, containing a full, clear, and exact description, reference being had to the accompanying drawings, forming a part hereof.

My invention relates to certain new and useful improvements in brick ice-cream containers, and has for its primary object the construction of a container and a detachable connection carried by the container for preventing the container from floating when empty or partially empty, and also has a means for holding the container in a fixed position within the refrigerating chamber of an ice cream cabinet.

This invention is an improvement on an invention previously patented by me May 8th, 1906, Numbered 819,789.

In the drawings,

Fig. 1 is a vertical section taken on the line 1—1 of Fig. 2.

Fig. 2 a top plan view of an ice cream cabinet with the lid removed, and the improvements applied to the container.

Fig. 3 a fragmental side elevation of a container showing my improvement applied thereto, with the retaining wing removed.

Fig. 4 a section taken on the line 4—4 of Fig. 3.

Fig. 5 a perspective view of the retaining wing which I employ.

Fig. 6 a top plan view of the pocket in which the retaining wing is located.

Fig. 7 a bottom plan view of the same.

Fig. 8 a vertical section through the retaining wing and a side view of the block in which it is located, and a hook for holding the retaining wing in position.

Fig. 9 a similar view showing a modified construction for holding the retaining wing in the cabinet in place.

Referring to the drawings,

10 indicates an ice cream cabinet of the usual construction provided with a lid 11 and a draining tube 12. 13 indicates the ice cream container which is used preferably for brick ice cream and which container is provided with a lid 14. Secured on opposite sides of the container 13 are pockets 15 which are formed out of a single

piece of sheet metal by folding the portion 16 over the portion 17 and leaving an opening 18 therein. 19 indicates a vertical flange which is spaced apart from the portion 16, leaving an opening 19^a. The lower end of 60 the portion 16 is riveted to the portion 17 by means of a rivet 20, thus closing the lower end of the opening 18. The upper end of the portion 17 is riveted to the container 13 by means of rivets 21 passing 65 through an opening 22. The pockets 15 are permanently secured to the sides of the container 13, and being secured to the container directly opposite each other. Secured to the cabinet 10 on opposite sides thereof 70 and centrally on each side, are blocks 23 in which is formed a vertical channel 24. 25 indicates a retaining wing which is formed out of sheet metal and has a right angular portion 26 adapted to be inserted 75 in the opening 18, and a portion 27 adapted to be inserted in the opening 19^a. The retaining wing 25 may be inserted and removed from the pocket, and the portion 27 is adapted to be positioned in the slots 80 or channels 24. In order to retain the portion 27 of the wing in the slots 24, I employ hooks 28 which are pivotally secured to the blocks 23 by means of a screw 29. These hooks are adapted to be inserted over the 85 top edge of the portions 27, and thus secure the retaining wings within the channels 24. In Fig. 9 I have shown a modified form for holding the portion 27 in the slots, wherein I secure blocks 30 to the sides of the cabinet, 90 and a removable block 31. The removable block 31 being inserted between the blocks 30 and block 23. As previously pointed out the salient feature of my improvement is to provide a pocket secured to the container 95 and a detachable retaining wing adapted to be inserted within said pocket. Said retaining wing may be detachable for the purpose of shipping and packing, and should one become broke or bent, it can be removed 100 and another inserted.

Having fully described my invention, what I claim is:

1. An ice cream container comprising a container proper, a pair of pockets permanently secured to the container, one of which being positioned directly opposite the other, said pockets being provided with closed lower ends and a vertical channel, channel blocks, removable wings seated in the pock- 110

ets and in said channel blocks, and a hook for holding the wings in position within the blocks.

2. An ic cream container comprising a container proper, a pair of pockets permanently secured to the container, one of which being positioned directly opposite the other, said pockets being provided with closed lower

ends and a vertical channel, and a flange, channel blocks, removable wings seated in 10 the pockets and in said channel blocks, and a hook for holding the wings in position within the blocks.

In testimony whereof, I have signed my name to this specification.

CHARLES NELSON.
